(57) **CLAIM**

The ornamental design for a ball-shaped sensor light, as shown and described.

DESCRIPTION

FIG. 1 is a front perspective view of a ball-shaped sensor light, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view showing the ball-shaped sensor light's lamp and base portions in a separated position; and, FIG. 10 is another perspective view showing the ball-shaped sensor light's lamp and base portions in a separated position. The broken lines in the drawings illustrate the portions of the ball-shaped sensor light, which form no part of the claimed design.
